UNITED STATES PATENT OFFICE.

ROBERT M. FOTHERINGHAM, OF BUFFALO, NEW YORK.

BUFFING MACHINE.

Application filed August 18, 1924. Serial No. 732,662.

This invention relates to an improved machine for buffing or polishing articles constructed of metal, hard rubber or like material.

- 5 One of its objects is to provide a simple, compact and efficient machine of large capacity for expeditiously buffing or polishing articles with a minimum expenditure of power and labor.
- 10 Another object of the invention is to improve the mechanism for intermittently revolving the work carrier with a view of rendering it positive and reliable in action.

15 A further object is the provision of a portable machine of this character which is universally adjustable to adapt it to work of different varieties.

20 Other features of the invention reside in the construction and arrangement of parts which will be hereinafter fully described and particularly pointed out in the appended claim.

25 In the accompanying drawings: Figure 1 is a side elevation of a buffing machine embodying my improvements. Figure 2 is a fragmentary end view thereof. Figure 3 is an enlarged top plan view of the machine, partly in section. Figure 4 is an enlarged transverse vertical section on line 4—4, Fig. 30 1. Figure 5 is an enlarged vertical transverse section on line 5—5, Fig. 3. Figures 6 and 7 are transverse sections, similar to Fig. 5 showing the parts in different positions. Figure 8 is a fragmentary longitudinal section on line 8—8, Fig. 3. Figure 9 is an enlarged transverse section on line 9—9, Fig. 3. Figure 10 is a transverse section taken in the plane of line 10—10, Figure 3.

40 Similar characters of reference indicate corresponding parts throughout the several views.

45 In the preferred embodiment of the buffing machine shown in the drawings, the same is mounted on a suitable standard or pedestal 10 including a longitudinally adjustable slide or supporting block 11 having clamping bolts 12 passing through longitudinal slots 13 formed in the top of the standard, as shown in Figs. 1 and 2. Guided on this slide for adjustment transversely of the standard is a

50 14 having a bearing collar 15 projecting from its top side upon which the turret-head or main frame 16, supporting the working parts of the machine, is revolvably mounted. The adjustment of the turret 14 for moving the machine toward and from the buffing

wheel 17, shown by dotted lines in Fig. 4, preferably consists of a manually-controlled horizontal adjusting screw 18 held against movement lengthwise of the slide-block 11 60 and engaging a swivel-nut 19 depending from said turret and in axial alinement with the bearing collar 15 thereof. A set screw 20 may be employed for locking the machine-frame 16 in a set position on its bearing collar. By 65 mounting the machine in this manner, the same is universally adjustable to enable it to be set in a variety of positions relative to the buffing or polishing wheel to suit different kinds of work.

70 The numeral 21 indicates a longitudinal shaft which is journaled at its ends in suitable bearings 22 formed on the machine-frame 16 and which is adapted to be intermittently rotated. Secured to its front end is a work-carrier chuck head in the form of a circular head 23 having a plurality of chucks or work-holders 24 disposed in a circular series and projecting from its front face for receiving the articles 25. These chucks are slotted in 80 the direction of their length, as shown at 26, whereby the resulting resilient jaws are permitted to expand and contract more or less. Each chuck is mounted on an arbor or spindle 27 of tubular form, which is supported in a bearing 28 on the carrier-head 23 and on the inner end of which a pinion 29 is fixed, as shown in Fig. 3.

85 The several chucks are adapted to be driven successively as the carrier-head is intermittently rotated. The preferred mechanism for accomplishing the result is constructed as follows:

90 30 indicates a driving shaft arranged parallel with the shaft 21 and journaled in suitable bearings 31 on the machine-frame 16. At its front end is secured a driving pinion 32 with which the annular row of chuck pinions 29 are adapted to successively engage for rotating the chucks 24 as they are presented to 100 the buffing wheel 17. This shaft is driven by an electric or other suitable motor 33 secured to a bracket 34 attached to the frame of the machine. A pinion 35 mounted on the motor-shaft 36 meshes with a gear wheel 37 loosely 105 mounted on the shaft 21, while a pinion 38 connected to said gear wheel to turn therewith, as shown in Fig. 8, meshes with a gear wheel 39 fixed on the driving shaft 30. Through this train of gearing the driving 110 pinion 32 is driven in the proper direction and at the proper speed to successively rotate

the several chucks as the chuck-head is intermittently revolved.

The mechanism for intermittently revolving the chuck-head 23 is preferably constructed as follows:

Fixed on the driving shaft 30 is a pinion 40 meshing with a driving member or gear wheel 41 loosely mounted on the shaft 21. Rotatable with the gear wheel 41 and secured thereto by screws 42 or otherwise is a segmental carrier 43 at one end of which a vertically-swinging feed pawl 44 is fulcrumed, as shown at 45. At the other end of this carrier is a releasing roller 46. Said pawl is provided with a tooth 47 adapted to interlock with one or another of the corresponding teeth of a driven member or ratchet-wheel 48 disposed alongside the gear wheel 41 and fastened by a set screw 49 to a spool 50 pinned or otherwise fixed to the shaft 21. A spring 51 serves to normally hold the pawl 44 out of engagement with the teeth of the ratchet wheel and a stop-lug 52 on the tail of the pawl is adapted to engage the adjoining peripheral edge 53 of the carrier 43 for limiting the outward-swinging movement of the pawl, as shown in Fig. 5. During the operation of the machine, the gear wheel 41, together with the pawl-carrier 43, is rotated constantly at uniform speed, and for a fraction of a revolution the pawl 44 is engaged with the ratchet wheel to advance the chuck-head 23 a corresponding fraction of a revolution to successively present the various chucks to the buffing wheel. To this end, the driving shaft 30 has a roller 54 freely mounted thereon with which the outer curved face 55 of the pawl is adapted to contact for swinging the same inwardly against the resistance of its spring 51 into locking engagement with one of the teeth of the ratchet wheel, as shown in Figs. 6 and 7, thereby compelling the ratchet-wheel to turn with the gear wheel 41 and transmitting motion to the shaft 21 to revolve the chuck-head 23. As soon as the curved face of the pawl clears said contact-roller, the spring 51 returns the pawl to the released position shown in Fig. 5. During the period that the pawl is released and again engaged with the ratchet-wheel, the chuck head is at rest, and the article 25, borne by that chuck just presented to the buffing wheel is being polished.

In order to positively lock the chuck-head 23 against rotation during its period of rest when the buffing or polishing operation is being effected, a locking wheel 56 is employed. The latter is disposed at one side of the ratchet wheel 48 and fastened by a set screw 57 to the spool 50. In its periphery, this locking wheel has a plurality of equi-distant radial notches 58, there being as many notches as there are teeth on the ratchet wheel and as there are chucks on the head 23. Fulcrumed on the shaft 30 is a vertically-swinging lock-

ing pawl 59 having a tooth 60 which normally bears on the periphery of the locking wheel, as shown in Fig. 7, and which is adapted to engage one or another of the locking notches 58. A spring 61 attached to an arm 62 of this pawl acts to urge its tooth toward the periphery of the locking wheel.

For the purpose of effecting the automatic release of the locking pawl 59 from engagement with its locking wheel 56 at a predetermined point, that is, just prior to the engagement of the feed pawl 44 with the ratchet wheel 48 to intermittently rotate the chuck-carrying head, said locking pawl is provided with a trip-arm 63 extending in the path of movement of the releasing roller 46 mounted on the segmental carrier 43. When this roller engages the curved face of the trip arm, Fig. 6, it swings the locking pawl away from the locking wheel to withdraw its tooth 60 from engagement with the corresponding notch 58, thereby releasing the chuck-head 23 and permitting its rotation with the ratchet-wheel the moment the feed pawl 44 is engaged therewith, which operation takes place immediately after the release of the locking pawl as seen in Fig. 6.

By mounting the ratchet wheel 48 and the locking wheel 56 on the spool 50 fixed to the chuck-head shaft 21, they may be readily adjusted circumferentially relatively to each other by simply loosening their set screws 49 and 57, respectively, to properly synchronize said wheel, so that the rotary chuck-head 23, which is normally locked when at rest, will be unlocked just before the feed pawl is engaged with the ratchet wheel.

Means are provided for automatically releasing the chucks from gripping engagement with the articles supported by them and also for partially ejecting such articles from the chucks. The preferred mechanism for accomplishing these results is shown in Figs. 1, 3 and 4 and preferably constructed as follows:

Extending through the bore of each chuck-spindle 27 is a combined chuck release and article ejector which consists of a rod or plunger 64 capable of movement lengthwise of the spindle and provided at its inner or threaded end with a cylindrical nut 65 fitted in a counter-bore 66 formed in the corresponding end of said spindle. At its front end, this rod has a tapered portion or head 67 which extends into the corresponding split-end of the chuck for the purpose of expanding its jaws when the rod is moved inwardly, or permitting contraction thereof when said rod is moved outwardly. As shown in Fig. 3, this rod-head may normally project slightly beyond the open-end of the chuck so that when the rod is forced outwardly, its head will abut against the article 25 and partially eject it from the chuck, as shown by dotted lines in connection with the

lowermost chuck in Fig. 1. A round-head screw 68 or equivalent member is fitted into the outer head of the nut 65 and arranged to traverse an arcuate, double-ended cam 69 fastened to the adjacent end of the machine-frame, said cam acting to automatically push the rod 64 forwardly to permit contraction of the chuck-jaws and to release and partially eject the article therefrom. A coil spring 70 applied to this rod and bearing at one end against the nut 65 and at its other end against a washer or shoulder 71 functions to normally retain the rod in its retracted position, shown in Fig. 3. The length of the cam 69 is such that the rod 64 is held in its projected position for two or three steps of the intermittent rotary movement of the chuck-head 23, so as to give the operator plenty of time to effect the complete removal of the polished articles from their chucks.

Briefly stated, the operation of the machine is as follows:—

After placing the articles to be buffed or polished on the chucks, the electric motor is started, transmitting motion to the driving pinion 32 and successively revolving the chucks 24 as their driven pinions 29 mesh with said driving pinion during the step by step movement of the head 23. Intermittent rotary movement is automatically transmitted to said head in the manner heretofore described, through the medium of the ratchet wheel 48 and feed pawl 44, which latter is normally held out of engagement with said wheel by the spring 51 and swung into engagement therewith at a predetermined point upon encountering the roller 54 as shown in Fig. 7. Immediately after the completion of a step of the chuck-head, the tooth of the locking pawl 59 drops into a corresponding notch of the locking wheel 56, thereby positively holding the chuck-head against rotation during the time an article is presented to the buffing wheel. When this interval of

rest has elapsed, the locking pawl is automatically withdrawn from the locking wheel by the releasing roller 46 engaging the trip arm 63 of said pawl, as shown in Fig. 6, after which the feed pawl again engages the ratchet wheel to advance the chuck-head another step and present the next article to the buffing wheel and so on. While each chuck is in its active position, it is constantly rotated at a slower speed than the buffing wheel, thus presenting all portions of the article to the buffing wheel. After passing the buffing wheel, the polished articles are removed from their chucks and replaced by others without stopping the machine.

This improved machine, while manifestly simple and compact in construction, is efficient and reliable in operation, it effects the expeditious buffing or polishing of various articles with a minimum expenditure of power and it can be operated by unskilled labor.

I claim as my invention:

A buffing machine comprising a supporting frame, a rotatable chuck head, an annular row of chucks supported in said head and having pinions, a shaft carrying the chuck head, means for rotating the chuck pinions when they arrive at a certain station, and for intermittently rotating the chuck head shaft to bring the chucks in succession to said station, said means consisting of a continuously rotating shaft arranged parallel with the chuck head shaft, a pinion thereon to be engaged by said chuck pinions when at said station for rotating the chucks, a second pinion on the said continuously rotating parallel shaft, a gear mounted coaxially with relation to the chuck head shaft rotated continuously from the said second pinion on the said parallel shaft, and means for transmitting motion from said continuously driven gear intermittently to the chuck head shaft, substantially as described.

ROBERT M. FOTHERINGHAM.
